ROLLING MILL

Lorenz Iversen, Pittsburgh, Pa., assignor to
 Mesta Machine Company, Pittsburgh, Pa., a
 corporation of Pennsylvania

Application August 26, 1933, Serial No. 686,942

5 Claims. (Cl. 80—31.1)

My invention relates to rolling mills and, in particular, to a mill having vertical rolls.

In the manufacture of rolled metal articles such as round bars, it has been considered desirable heretofore to subject the articles to the action of a stand of vertical grooved rolls after passing through the last stand of horizontal grooved rolls. The mills now used for this purpose are conventional vertical mills driven from below by a line shaft and bevel gearing. This construction is cumbersome to assemble and difficult to adjust and keep in repair. It is also very important to have the pass of the vertical mill as close as possible to the pass of the preceding horizontal mill. It is an object of my invention to provide an improved vertical rolling mill structure which overcomes the disadvantages of similar mills known previously.

In accordance with my invention, I provide a base secured to a suitable foundation, and a supporting frame which is adapted for adjustment along the base transversely of the path of travel of material through the mill. The supporting frame is provided with abutments on which is carried a vertically adjustable cradle. The cradle supports two roll housings on opposite sides of the pass and each housing contains bearings for supporting a vertical backing up roll which gives lateral support to a vertical working roll preferably having a grooved surface.

The backing rolls are driven by separate motors directly connected thereto and mounted on the roll housings. The working rolls are frictionally driven by the backing rolls. Means are provided for individually adjusting each working roll axially. One of the roll housings is fixed against lateral movement in the cradle, while the other is adjustable horizontally therein.

In order to synchronize the speed of the vertical working rolls with that of the horizontal rolls in the last stand of a mill, I provide a generator adapted to be mechanically driven by the motor or other means which drives the last horizontal roll stand. The motor of a motor-generator set is electrically driven by this generator and the generator of the motor-generator set supplies current to the two motors which drive the vertical backing rolls.

For a complete understanding of the invention, reference is made to the accompanying drawings illustrating a present preferred embodiment. In the drawings—

Figure 1 is an elevation partly in section, the plane of the section being indicated by the line I—I of Figure 2;

Figure 2 is a sectional view along the line II—II of Figure 1, showing parts in plan;

Figure 3 is a partial sectional view along the line III—III of Figure 1, showing the roll housings and a portion of the cradle apart from the supporting frame;

Figure 4 is a sectional view along the line IV—IV of Figure 2;

Figure 5 is a sectional view on the line V—V of Figure 2;

Figure 6 is a side elevation with parts in section along the line VI—VI of Figure 1; and

Figure 7 is a schematic diagram illustrating the electrical and mechanical connections constituting the drive for the vertical roll stand.

Referring now in detail to the drawings, the illustrated embodiment of the invention comprises a base 10 having bed rails 11 extending longitudinally thereof. A supporting frame 12 is mounted on the bed rails 11 for adjustment therewith. A screw shaft 13 is pinned to one end of the frame 12 and traverses a threaded sleeve 14. The sleeve 14 is driven by a gear 15 meshing with a pinion 16. A motor 17 is coupled to the shaft of the pinion 16. A gear box 18 on one end of the base 10 houses the gear 15 and pinion 16. The frame 12 may be secured in adjusted position on the base 10 by means of T-bolts 19 and keys 20 or other suitable means.

Abutments 21 extend upwardly from the frame 12 adjacent opposite ends thereof. A transverse shaft 22 is journaled in the abutments 21 and is provided with pinions 23. A double reduction gear 24 mounted in a suitable gear box on the right hand abutment 21 as viewed in Figure 2, actuates the shaft 22 when a hand wheel 25 is turned. The double reduction gear comprises a pinion 26, a gear 27, a worm 28 and a worm wheel 29. The gear 27 and the worm 28 are keyed to a common shaft journaled in the gear box.

A cradle or secondary supporting member 30 is vertically adjustable on the abutments 21 along guides 31. Keepers 32 cooperate with the guides to secure the cradle therein. The cradle comprises a generally box-like casting having windows 33 in opposite sides thereof and an open top and bottom. Racks 34 are formed on the exit side of the cradle for engagement by the pinions 23. The cradle has a vertical opening 35 for receiving roll housings 36 and 37.

The roll housings are of substantially yoke form in section, as shown in Figure 2. The roll housing 36 is normally maintained in abutting engagement with the end of the opening 35 in the cradle 30, by means of springs 38. The hous-

ing 37 is normally urged toward the right-hand end of the opening 35, as shown in Fig. 1, by means of a spring 40. The housing 37, however, is adjustable laterally in the cradle by means 5 of adjusting screws 41 traversing threaded sleeves 42 fitted in recesses at the right-hand end of the cradle 30. Worm wheels 43 are secured to the screws 41 and are actuated by worms 44 carried on a shaft 45 journaled vertically in the cradle. A hand wheel 46 on the shaft 45 permits the screws 41 to be adjusted to shift the housing 37 toward or away from the housing 36.

Each of the housings 36 and 37 is provided with a working roll 47 and a backing roll 48 which gives lateral support to, and drives the working roll. The surfaces of the working rolls 47 are preferably grooved except for portions adjacent their ends. The backing rolls 48 are recessed at 49 to clear the grooved portions of the rolls 47, leaving enlarged end portions for engaging the ungrooved portions of the working rolls. The rolls 48 are journaled in anti-friction bearings of any suitable type positioned in bearing boxes 50 seated in the housings. The upper bearing box 50 may preferably embody a thrust bearing for supporting the weight of the roll 48. The working rolls 47 are similarly journaled in bearings contained in bearing boxes 51. Hook bolts 51a engaging the bearing boxes 51 of the working rolls and actuated by springs 51b bearing against shoulders on the roll housings, serve to keep said working roll in frictional driving engagement with its backing roll. The roller bearings for the working rolls may be of conventional type. Screws 51d hold the housings 36 in contact with the exit side of the cradle. Driving motors 52 are coupled to the backing rolls 48 and are supported on extensions or shelves 53 on the housings 36 and 37.

40 The upper bearings for the rolls are shown in detail in Figures 4 and 5. The upper bearing boxes 51 are provided adjacent the lower ends with conventional roller bearings 54 operating between race-ways 55 and 56 in the boxes 45 and on the shafts of the rolls 47 respectively. Internally threaded sleeves 57 are seated in the upper ends of the boxes 51 by integral supporting flanges. Additional sleeves 58 threaded externally are adjustably positioned in the sleeves 57. An anti-friction thrust bearing comprising race-ways 59 and rollers 60 is carried in the sleeve 58. A lock nut 61 secures the sleeves 57 and 58 together. A collar 62 is secured to the reduced end of the roll 47 by a key 63 and engages the anti-friction thrust bearing to support the roll. A cover 58a is bolted to sleeve 58 and this cover has holes drilled around its periphery by means of which the sleeve and cover 55 may be turned when desired, to adjust the rolls axially.

60 The bearing box 51 is supported in the roll housing in the manner shown more clearly in Figure 5. The housing 36 is seated in the opening 35 in the cradle 30 by means of recesses in the sides of the opening and shoulders 65 resting thereon. The housing 36 has grooves 66 and flanges 67. The bearing box 51, which is rectangular in outline (as shown in Figure 2), has 65 lugs adapted to enter the grooves 66. Keys 68 secure the box in position. Hold-down clamps 69 are bolted to the cradle 30. At one side, the clamps engage the housing 36 as shown in Figure 5. The other side of each clamp engages 70 a lug 70 integral with the cradle.

Figure 7 illustrates schematically the drive for the mill shown in Figures 1 to 6. In Figures 6 and 7, the last stand of horizontal rolls of a mill is indicated at 71. This stand of rolls is driven by a motor 72 through a pinion stand 73. A generator 74 is coupled to the shaft of the motor 72. The generator 74 is electrically connected to the motor 75 of a motor generator set 76. The generator 77 of the motor generator set 76 is electrically connected to the 10 motors 52 which are directly coupled to the backing rolls 48 of the vertical stand. It will be apparent that this drive for the rolls of the vertical stand permits the working rolls thereof to be properly synchronized as to linear speed 15 with the horizontal rolls 71.

The vertical roll stand illustrated and described herein is characterized by numerous advantages over such structures as known to the prior art. The rolls of the mill are capable of 20 a wide variety and range of adjustments. The various parts of the mill are readily accessible and can be easily removed for inspection or replacement. The friction drive of the work rolls from the backing rolls is characterized by great 25 simplicity and high efficiency. The vertical mill may be located very close to the center of the leading horizontal mill.

It will be apparent that the mill is adjustable 30 transversely so that the pass between the working rolls may be properly aligned with the path of the advancing material by operating the motor 17 to turn the adjusting screw shaft 13. This adjustment is made so that the left-hand working roll carried by the housing 36 has the proper relation to the path of material. When the frame 12 has been properly adjusted transversely, it may be secured in adjusted position in the manner disclosed, and the right-hand working roll adjusted to provide a pass of the desired size 40 by operation of the hand wheel 46. The roll assembly may be adjusted vertically by turning the hand wheel 25 to raise or lower the entire cradle as a unit. The working rolls may be adjusted endwise individually, furthermore, by 45 means of the threaded sleeves 57 and 58.

The roll housings 36 and 37 may readily be removed by releasing the clamps 69 and the springs 39 and 40. The working rolls may be moved by knocking out the keys 68 and shifting 50 the bearing boxes laterally out of the jaws of the housings 36 or 37. The working rolls are always maintained in driving engagement with the backing rolls by the hook bolts 51a. The axes of the working and backing rolls lie in a vertical plane 55 on the entrance side of the mill so that the latter can be positioned quite close to the last horizontal mill stand as shown in Figure 6. The easy adjustability of the working rolls makes it possible 60 readily to direct the material into different grooves on the rolls. Similarly, the correction of the pass to compensate for wear is also easily accomplished.

Although I have illustrated and described herein but one preferred embodiment of the invention, it will be apparent that many changes therein may be made without departing from the spirit of the invention or the scope of the appended claims.

I claim:

1. In a rolling mill, a cradle mounted for vertical adjustment, a pair of independent roll housings removably seated in said cradle, at least one of said housings being adjustable to and from the other, backing rolls journaled vertically in said housings, working rolls similarly journaled 75

therein, and an adjustable thrust bearing supporting at least one of the working rolls whereby it may be adjusted axially in its housing.

2. In a rolling mill, an abutment for sustaining horizontal thrusts to which the mill is subject, means supporting the abutment for adjustment transversely of the path of material traversing the mill, a cradle so mounted on said abutment as to preclude relative movement therebetween transversely, said cradle being adjustable vertically on the abutment, a pair of independent roll housings removably seated in the cradle, a roll journaled vertically in each housing, each housing having a shelf projecting thereover and a motor on said shelf for driving said roll.

10 3. A rolling mill comprising a base having an upstanding abutment thereon, a cradle slidable vertically on said abutment, a pair of independent housings seated in said cradle, each housing including two pairs of vertically aligned bearings,

working and backing rolls journaled in said bearings, each of said housings having a shelf extending over said bearings and a motor on said shelf for driving the backing roll.

4. A rolling mill comprising a cradle mounted for vertical movement, and a pair of independent, open sided housings removably seated in the cradle with their open sides adjacent, work rolls and backing rolls journaled in each housing, the faces of the work rolls projecting outwardly of the 10 open sides of the housings into contact with each other, each housing having a shelf thereover and a motor on said shelf for driving the work roll journaled therein.

5. The apparatus defined by claim 4 characterized by said working roll bearings being movable laterally in said housings, and means for retracting them until the working rolls engage the backing rolls.

LORENZ IVERSEN. 20
